CLAIM

The ornamental design for an LED light, as shown and described.

DESCRIPTION

FIG. 1 shows is a perspective view of a LED light showing my new design;

FIG. 2 is a top plan view thereof;

FIG. 3 is a front elevational view thereof;

FIG. 4 is a bottom plan view thereof;

FIG. 5 is a left side elevational view thereof;

FIG. 6 is a right side elevational view thereof;

FIG. 7 is a rear elevational view thereof;

FIG. 8 is a partial enlarged perspective view thereof; and, FIG. 9 is a partial enlarged perspective view thereof with the side cover removed.

The broken lines illustrate portions of the LED light which form no part of the claimed design.
